UNITED STATES PATENT OFFICE.

FRANCIS KORFF, OF LANSING, MICHIGAN, ASSIGNOR TO KORFF MFG. CO., OF LANSING, MICHIGAN.

SERVING APPARATUS.

1,028,942.

Specification of Letters Patent. Patented June 11, 1912.

Application filed October 10, 1911. Serial No. 653,936.

To all whom it may concern:

Be it known that I, FRANCIS KORFF, a citizen of the United States, residing at the city of Lansing, county of Ingham, and State of Michigan, have invented certain new and useful Improvements in Serving Apparatus, of which the following is a specification.

This invention relates to improvements in serving apparatus.

10 My improved serving apparatus is especially designed by me for use in holding rolls of gummed tape, cutting into strips of the desired length and moistening the same. My invention can, however, be readily 15 adapted for use in applying an adhesive to the tape or to sheets of paper or fabric delivered from a roll or the like.

I use the term "moistening" in this specification as the embodiment shown is provided with a moistening roller. It will, however, be understood that the invention comprehends means for applying adhesive as well as moisture.

The main objects of this invention are, 25 first, to provide an improved combination roll holder cutter and moistening or adhesive applying device for rolls of tape or the like. Second, to provide a device of the class described, in which the strips delivered have 30 finger-hold portions at each end which are not supplied with moisture or adhesive. Third, to provide a device of the class described which is simple and economical in structure and very convenient to use.

35 Further objects, and objects relating to structural details, will definitely appear from the detailed description to follow.

I accomplish the objects of my invention by the devices and means described in the 40 following specification.

The invention is clearly defined and pointed out in the claims.

A structure which is a preferred embodiment of my invention is clearly illustrated 45 in the accompanying drawing, forming a part of this specification, in which:

Figure I is a perspective view of a structure embodying the features of my invention. Fig. II is a detail plan view thereof, 50 the roll holder being omitted. Fig. III is a detail vertical section taken on a line corresponding to line 3—3 of Fig. II, the tape support and cutter being shown by dotted lines in its raised position and by full lines 55 in its cutting position. Fig. IV is a detail

vertical section taken on a line corresponding to line 4—4 of Fig. II with the tape support and cutter shown by full lines in its elevated position and by dotted lines in its lowered or tape moistening position. 60

In the drawings, similar reference characters refer to similar parts throughout the several views, and the sectional views are taken looking in the direction of the little arrows at the ends of the section lines. 65

Referring to the lettered parts of the drawing, the base 1 is preferably provided with feet 2 at its corners. The water or adhesive receptacle 3, is in the structure illustrated, formed integrally with the base, the 70 base illustrated being a casting. The tape roll holder consists of a pair of side plates or disks 5 which clamp the ends of the tape spool 6, indicated by dotted lines in Fig. I. The yoke-like support 7 is mounted on the 75 base at one end thereof, the spool spindle 8 being threaded to receive the clamping nut 9. By this simple means, tension may be applied to the roll of tape. The water or adhesive applying roller 10 is provided with 80 suitable journals at its ends arranged in notch-like bearings in the ends of the receptacle 3.

Between the roll holder and the receptacle 3, I arrange a U-shaped bracket 11 having a 85 cross rod 12 at its upper end under which the tape 13 is passed (see Figs. III and IV). The tape jaw 14 coacts with this fixed rod-like jaw 12 to provide tape holder or feed jaws, the tape being arranged over the jaw 90 14 which is preferably in the form of a blade spring having a forwardly projecting flange 15 at its upper end. The jaw 14 is provided with a flange-like foot 16 at its lower end which rests on the bottom of the 95 bracket 11 and is secured by the bracket attaching screws 17.

I provide a combined tape cutter and support which, in the structure illustrated, consists of a pair of plates 18 and 19 spaced to 100 provide a tape slot or to receive the tape therebetween, as is clearly illustrated in Figs. III and V. The plate 18 is provided with downwardly-projecting ears 20 at its ends which embrace the arms of the bracket 105 11 and are pivotally mounted on the rod 21. The spring 22 is coiled about the pivot rod 21, one end of the spring being engaged with the bracket and the other engaging the end side of the plate 19. The forward edge 110

23 of the plate 18 is a cutting edge. The cutter thus supported, is adapted to swing toward and from the tape holder or feed jaws and the moistening roller. A catch or 5 pivoted stop 24 is provided to support the cutter in an intermediate position, as shown in Fig. III, which is its cutting position. The catch 24 is, in the structure illustrated, mounted on the cross bar 12.

- 10 In use, the tape is drawn down over the moistening roller, as shown in Fig. IV, until a strip of the desired length is secured. The pull on the tape swings the cutter from the position shown by full lines in Fig. IV to 15 the position shown by dotted lines into close proximity with the moistening roller. When the pull on the tape is released, the cutter swings to the cutting position shown by full lines in Fig. III, against the catch or stop 20 24 which automatically swings into engaging position. The tape is then severed by pulling against the cutting edge 23 of the cutter. When it is desired to secure another piece, the catch 24 is released, which allows 25 the cutter to swing to the position shown by dotted lines in Fig. III and full lines in Fig. IV. The cutter swings back exposing the end of the tape to provide a finger piece. The support is so arranged relative to the 30 moistening roller that the end of the portion severed does not come in contact with the moistening roller, and an unmoistened finger piece is provided at each end of the severed strip.
- 35 My improved device is simple and economical in structure and may be very quickly and easily operated. I have illustrated and described the same in detail in an embodiment which I find very satisfactory. I have not attempted to illustrate or 40 describe the various modifications possible as the disclosures made herein will be sufficient to enable those skilled in the art to which this invention relates, to adapt my 45 improvements to the uses desired.

Having thus described my invention, what I claim is new and desire to secure by Letters Patent is:

1. In a structure of the class described, 50 the combination with the base, of a roll holder mounted thereon; a moistening roller; a U-shaped bracket arranged on said base between said roll holder and moistening roller; a cross rod at the upper end of said 55 bracket under which the tape is passed; a blade spring having a forwardly projecting flange at its upper end arranged to support the tape and to coact with said rod to provide tape holder jaws; a tape cutter and support comprising a pair of plates spaced to receive the tape therebetween, the forward edge of the upper plate being adapted as a cutter, said upper plate having down-turned pivot ears at its ends pivotally 60 mounted on said bracket to swing toward 65 and from said tape holder jaws and said moistening roller; a spring arranged to hold said cutter yieldingly upward, the tops of the arms of the bracket being adapted to serve as stops for said cutter; and a catch pivoted on said cross rod to engage said cutter when it is in an intermediate position, for the purpose specified.

2. In a structure of the class described, 70 the combination with the base, of a roll holder mounted thereon; a moistening roller; a U-shaped bracket arranged on said base between said roll holder and moistening roller; a cross rod at the upper end of said bracket under which the tape is passed; a blade spring having a forwardly projecting flange at its upper end arranged to support the tape and to coact with said rod to provide tape holder jaws; a tape cutter and support pivotally mounted on said bracket to swing toward and from said tape holder jaws and said moistening roller; a spring arranged to hold said cutter yieldingly upward; and a catch.

3. In a structure of the class described, 75 the combination with the base, of a roll holder mounted thereon; a moistening roller; a U-shaped bracket arranged on said base between said roll holder and moistening roller; a cross rod at the upper end of said bracket under which the tape is passed; a blade spring having a forwardly projecting flange at its upper end arranged to support the tape and to coact with said rod to provide tape holder jaws; a tape cutter and support pivotally mounted on said bracket to swing toward and from said tape holder jaws and said moistening roller; a spring arranged to hold said cutter yieldingly upward; and a catch.

4. In a structure of the class described, 80 the combination with the base, of a roll holder mounted thereon; a moistening roller; a U-shaped bracket arranged on said base between said roll holder and moistening roller; a cross rod at the upper end of said bracket under which the tape is passed; a blade spring having a forwardly projecting flange at its upper end arranged to support the tape and to coact with said rod to provide tape holder jaws; and a tape cutter and support comprising a pair of plates spaced to receive the tape therebetween, the forward edge of the upper plate being adapted as a cutter, said upper plate having down-turned pivot ears at its ends pivotally 85 mounted on said bracket to swing toward and from said tape holder jaws and said moistening roller.

5. In a structure of the class described, 90 the combination with the base, of a roll holder mounted thereon; a moistening roller; a U-shaped bracket arranged on said base between said roll holder and moistening roller; a cross rod at the upper end of said bracket under which the tape is passed; a blade spring having a forwardly projecting flange at its upper end arranged to support the tape and to coact with said rod to provide tape holder jaws; a tape cutter and support pivotally mounted on said bracket to swing toward and from said tape holder jaws and said moistening roller; and a catch arranged to engage said cutter when it is in an intermediate position, for the purpose specified.

6. In a structure of the class described, 95 the combination with the base, of a roll holder mounted thereon; a U-shaped bracket; a cross rod at the upper end of said bracket under which the tape is passed; a blade spring 100

- having a forwardly projecting flange at its upper end arranged to support the tape and to coat with said rod to provide tape holder jaws; a tape cutter and support comprising 5 a pair of plates spaced to receive the tape therebetween, the forward edge of the upper plate being adapted as a cutter, said upper plate having down-turned pivot ears at its ends pivotally mounted on said 10 bracket to swing toward and from said tape holder jaws; a spring arranged to hold said cutter yieldingly upward, the tops of the arms of the bracket being adapted to serve as stops for said cutter; and a catch pivoted 15 on said cross rod to engage said cutter when it is in an intermediate position, for the purpose specified.
6. In a structure of the class described, the combination of a roll holder mounted 20 thereon; a U-shaped bracket; a cross rod at the upper end of said bracket under which the tape is passed; a blade spring having a forwardly projecting flange at its upper end arranged to support the tape and to coat 25 with said rod to provide tape holder jaws; a tape cutter and support pivotally mounted on said bracket to swing toward and from said tape holder jaws; a spring arranged to hold said cutter yieldingly upward; and a 30 catch pivoted on said cross rod to engage said cutter when it is in an intermediate position, for the purpose specified.
7. In a structure of the class described, the combination of a roll holder; a moistening 35 device; tape holder jaws comprising a fixed jaw and a coacting spring jaw, said tape being passed under the fixed jaw and over the spring jaw; a tape cutter comprising a pair of plates spaced to receive the 40 tape therebetween, the forward edge of the upper plate being adapted as a cutter, pivotally mounted between said tape holder jaws and moistening device to swing toward and from said tape holder jaws and said moistening 45 device; a spring arranged to hold said cutter yieldingly upward; and a catch arranged to engage said cutter when it is in an intermediate position, for the purpose specified.
- 50 8. In a structure of the class described, the combination of a roll holder; a moistening device; tape holder jaws comprising a fixed jaw and a coacting spring jaw, said tape being passed under the fixed jaw and 55 over the spring jaw; a tape cutter pivotally mounted to swing toward and from said tape holder jaws and said moistening device; a spring arranged to hold said cutter yieldingly upward; and a catch arranged to engage said cutter when it is in an intermediate position, for the purpose specified.
5. In a structure of the class described, 60 mounted to swing toward and from said tape holder jaws and said moistening device; a spring arranged to hold said cutter yieldingly upward; and a catch arranged to engage said cutter when it is in an intermediate position, for the purpose specified.
9. In a structure of the class described, 65 the combination of a roll holder; a moistening device; feed jaws comprising a fixed jaw and a coacting spring jaw, the tape being passed under the fixed jaw and over the spring jaw; a cutter comprising a pair of plates spaced to receive the tape, the forward edge of the upper plate being adapted as a cutter pivotally mounted to swing toward and from said feed jaws; and a catch arranged to support said cutter in an intermediate position, for the purpose specified.
10. In a structure of the class described, 70 the combination of a roll holder; feed jaws comprising a fixed jaw and a coacting spring jaw, the tape being passed under the fixed jaw and over the spring jaw; a cutter comprising a pair of plates spaced to receive the tape, the forward edge of the upper plate being adapted as a cutter pivotally mounted to swing toward and from said feed jaws; and a catch arranged to support said cutter in an intermediate position, for the purpose specified.
11. In a structure of the class described, 75 the combination of a roll holder; a moistening device; a holder; a cutter having a tape slot therein, said cutter being mounted to swing toward and from said holder and said moistening device; a spring arranged to urge said cutter toward said holder; and a catch arranged to support said cutter in an intermediate position.
12. In a structure of the class described, 80 the combination of a roll holder; a holder; a cutter having a tape slot therein, said cutter being mounted to swing toward and from said holder and said moistening device; a spring arranged to urge said cutter toward said holder; and a catch arranged to support said cutter in an intermediate position.
- In witness whereof, I have hereunto set my hand and seal in the presence of two 85 witnesses.
